Primary Examiner — Kendra Leslie Hamilton(74) *Attorney, Agent, or Firm* — Birch, Stewart, Kolasch & Birch, LLP(57) **CLAIM**

The ornamental design for a cap for syringe, as shown and described.

DESCRIPTION

FIG. 1 is a front elevation view of a cap for syringe showing our new design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof;

FIG. 7 is a front perspective view thereof; and,

FIG. 8 is a front cross-sectional view of the cap for syringe of FIG. 1, taken in the direction of line 8-8 of FIG. 5.

1 Claim, 8 Drawing Sheets(56)
